TRAVELING DESK SET

Solomon Kaufman, New York, N. Y.

Application January 30, 1951, Serial No. 208,546

1 Claim. (Cl. 58—56)

1
This invention relates to a combined travel clock and desk set.

The principal object of this invention is the provision of a compact travel clock and desk set comprising a case, a clock mounted in said case and one or more fountain pens or the like also mounted within said case. The case has a hinged cover which may be raised to open position or lowered to closed position. The clock is pivotally mounted so that it may be swung upwardly to exposed, usable position or downwardly to its unexposed, travelling position. Similarly, the fountain pen is also pivotally mounted so that it may be swung upwardly to a handy, accessible position and downwardly to an out-of-the-way, travelling position. The clock and the fountain pen are also swivelly mounted for swivelling movement about vertical axes.

The travel clock and desk set constituting the present invention has many desirable features. In the first place, it is a very compact unit which occupies very little space in a travelling bag. The reason underlying this feature is very clear: The clock and fountain pen are adapted to pivot downwardly to what may be described as flat, horizontal positions in substantially the same horizontal plane and the case may be shaped accordingly, that is, to a correspondingly flat shape.

Another object of this invention is the provision of a travel clock and desk set of the character described which is provided with at least one well into which the clock may pivot when it is swung downwardly to travelling position. Rising out of the well is a pedestal which supports the clock. Hence, when the clock is raised to exposed position, it stands on a relatively high level, no part of it being obscured by the sides or walls of the case. When it is lowered to travelling position, it fits at least in part into the well and, it therefore requires a relatively small case to accommodate it.

The well or wells are useful for another purpose, namely, to accommodate and hold articles of jewelry such as rings and earrings and the like. This is a very useful feature for people who travel since they invariably face the problem of putting their articles of jewelry in a convenient place whenever they spend the night away from home, as at a hotel or in a Pullman room. The wells in the case may also be used for carrying articles of jewelry and the like when the case is closed and tucked away in a travelling bag, suit case or the like.

A preferred form of this invention is shown in the accompanying drawing, in which:

2
Fig. 1 is a front view of an embodiment of a travel clock and desk set made in accordance with this invention, showing the clock and a fountain pen in upright positions, the case being partly broken away and in vertical section to expose the annular well formed in said case.

Fig. 2 is a side view of said travel clock and desk set, the case and its cover being partly broken away and in section.

10. Fig. 3 is a top view thereof.

Fig. 4 is a view somewhat similar to that of Fig. 1, but showing the clock in lowered, travelling position.

Fig. 5 is a side view of the case showing it in closed position.

Fig. 6 is a fragmentary, enlarged view, showing the case in vertical section and showing the swivel support for the clock.

Fig. 7 is a similar view showing the clock turned a full 90° from its position in Fig. 6 and showing both the swivel support and the pivotal support for the clock.

Fig. 8 is a plan view of the spring washer which acts upon the swivel support of the clock.

25. The combined travel clock and desk set herein claimed includes a case 10 to which a cover 12 is hingedly secured. Hinge 14 which connects the cover to the case is shown in Fig. 2. It will be noted in Fig. 3 that the case is somewhat rectangular in shape, and it will be seen in Fig. 1 that the cover is of correspondingly rectangular shape. It will be noted in Figs. 2 and 5 that the cover is hollow and that it is approximately as deep as the case.

35. Mounted on the floor of the case is a member 16 which supports the clock 18 and the fountain pen holder 20 and which also provides the well 22. This member 16 is bent upwardly in its center portion to form a hollow pedestal 24. It is also bent upwardly at its two end portions to form shoulders or pedestals 26 and 28, respectively. Well 22 is a depressed portion of member 16 which surrounds pedestal 24 and which is formed between said pedestal 24 and pedestals 26 and 28.

45. It will be seen in Fig. 7 that a screw 30 projects upwardly through a hole 32 formed in the center of pedestal 24. The head of the screw is disposed within said pedestal and its threaded end projects upwardly from the pedestal through said hole 32. A spring washer 34 is mounted on the shank of the screw, and it provides a spring bearing between the head of the screw and the top wall of the pedestal. Mounted on pedestal 24 and secured to the upwardly projecting, threaded

end of the screw, is a clock support 36. This clock support is approximately as long as the diameter of pedestal 24, and it is adapted to engage in swivelling movement on said pedestal about the vertical axis of the screw. The tension of spring washer 34 limits the freedom of movement of said clock support in the sense that it serves as a frictional brake to frictionally hold the clock support in any position about the vertical axis of the screw in which it may manually be placed. 10 It will hereinafter appear that it is by means of this swivelly mounted clock support that the clock may be turned either leftwardly or rightwardly on said vertical axis.

A pair of ball-shaped members 38 and 40 are secured to the bottom of the clock by means of screws 42. The heads of screws 42 are countersunk in said ball-shaped members 38 and 40 so that they are normally not in view. These ball-shaped members are spaced from each other a distance corresponding to the length of clock support 36 as Fig. 7 clearly shows. Projecting sidewardly from said ball-shaped members are pins 43 and 44, respectively, which are aligned with each other on a common, horizontal line. They project toward each other and into holes 46 and 48, respectively, formed in the opposite ends of clock support 36. It is by means of these pins 43 and 44 in holes 46 and 48 that the clock is adapted to pivot either upwardly or downwardly about a horizontal axis corresponding to the horizontal line on which said pins are disposed.

It will be apparent from the foregoing, that since the clock is mounted on the clock support 36, the clock and said clock support are adapted to swivel integrally with each other about the vertical axis of screw 30. Hence, the clock may be turned either to the left or to the right, which ever position happens to be more convenient at any particular time. The clock may also be tilted on its horizontal axis, that is the axis of pins 43 and 44, to any desired angular position on said horizontal axis. See the dot and dash lines of Figs. 2 and 3.

It will be noted that the clock case 50 in which the face of the clock is mounted, is considerably larger than the back portion 52 of the case in which the clockwork mechanism is mounted. It is the clock case 50 to which the ball-shaped members 38 and 40 are fastened. When it is desired to close the case 10 of the combined travel clock and desk set herein claimed, the clock is turned on its vertical pivot until its horizontal pivot is transverse to the length of said case 10. It is then swung downwardly on its horizontal pivot until it assumes its horizontal position shown in Fig. 4. In this position, the face of the clock faces upwardly and its clockwork case portion 52 projects downwardly into well 22. When the cover 12 is then swung downwardly to closed position, as shown in Fig. 5, it accommodates case portion 50 of the clock as well as ball-shaped members 38 and 40 and clock support 36.

A socket member 60 is secured to the top of pedestal 28. Movable mounted in said socket member 60 is a ball 62 and pinned to said ball is the fountain pen holder 20 above mentioned. It is by reason of this ball-and-socket connection that the fountain pen holder is adapted to swivel both upwardly and downwardly and also sidewardly to any desired position. This fountain pen holder is of conventional construction, and is adapted to receive a conventional foun-

tain pen 64. In Fig. 1, said fountain pen and fountain pen holder are shown in upright position and in Fig. 3 they are shown in prone position flat against member 16 of the case. When 5 cover 12 is in its closed position relative to case 10, it accommodates the fountain pen, fountain pen holder, and ball-and-socket support therefor.

If desired, a second socket member may be secured to the top of pedestal 28 and be so positioned relative to socket member 60 that two pens or other writing implements may lie side by side when in prone position.

The foregoing is descriptive of a preferred form of this invention, and it will be understood that this form may be modified in many ways within the broad scope of the invention. It may also be used in ways other than those shown in the drawing and for other purposes. For example, although the clock is shown on the right side of pedestal 24 in Fig. 4, it may equally as well be swung over to the left side of said pedestal. Well 22 may be used not only to accommodate the clock, but also to accommodate such articles of jewelry and trinkets as travelling people normally wear or carry with them on their travels.

Having thus described my invention, what I claim as new and desire to secure by Letters Patent, is:

In a combined travel clock and desk set, a case having a hinged cover, a hollow pedestal in said case, at least the top of said pedestal being circular, said pedestal having a hole formed in the center thereof, a screw projecting upwardly from the inside of said pedestal through said hole, a spring washer threaded on said screw between its head and the pedestal, a clock support secured to said upwardly projecting screw and being thereby adapted to engage in swivelling movement either rightwardly or leftwardly on the vertical axis of said screw, said clock support being at least as long as the diameter of the said pedestal top, a clock, a pair of lugs fixedly secured to the bottom of said clock in spaced apart relation, the space between the lugs being slightly greater than the length of the clock support to receive the clock support between them, a pair of cylindrical pins projecting inwardly coaxially toward each other from the confronting sides of said lugs, said pins extending into axially aligned holes formed in opposite ends of the clock support, said clock being thereby adapted to engage in pivotal movement either upwardly or downwardly on the horizontal axis of said pins; and a well formed in said case adjacent said pedestal to receive the clock when it pivots downwardly.

SOLOMON KAUFMAN.
